UNITED STATES PATENT OFFICE

WESLEY ERNEST JOHN, OF JOHANNESBURG, TRANSVAAL, SOUTH AFRICA

MEANS FOR PRODUCING A STRAIGHT-LINE MOTION OF LENSES

Application filed November 5, 1927, Serial No. 231,199, and in Great Britain February 15, 1927.

The present invention refers to systems in which a series of bodies is propelled, by rotary mechanism, through a closed path comprising a rectilinear section occupied by several of the bodies simultaneously; through which section the bodies are required to be moved at a speed having a fixed velocity ratio to the rotary driving mechanism.

10 Such systems have practical application in kinematograph apparatus in which the film is constantly moved and in which the bodies are carriers for lenses optically compensating for the film movement.

15 The present invention is of that type in which the bodies are unconnected and push one another through a fixed guide defining the rectilinear section.

The invention provides a construction in 20 which the propelling force can be applied to the bodies centrally of their length, thus avoiding the longitudinal tilting to which the bodies are liable in case the propelling force is applied by gear teeth engaging their 25 ends, as is necessary in some constructions. This result is attained according to the invention by propelling the bodies by means of an internally toothed wheel having, between the teeth, spaced pockets in which 30 the bodies are received; part of the pitch circle of the wheel being a part of the closed path of the bodies and the bodies being guided from said wheel into the rectilinear path. This arrangement also enables the 35 pushing action to be confined to those of the bodies which are in the rectilinear section and those immediately adjacent the ends of such section.

An example of the invention is illustrated in the accompanying drawings in 40 which—

Fig. I is a face view of a kinematograph mechanism with part of the front cover (13 Fig. II) broken away and some of the 45 bodies in section.

Fig. II is a section on II—II Fig. I.

Fig. III is an enlarged perspective view of the upper part of Fig. I.

2 is a thick disc fitted with a cover plate 3. 50 The disc is peripherally cut away to pro-

vide an annular channel 4 and is slotted on a chord to provide a rectilinear channel 5 communicating with the annular channel.

The disc and cover plate form a journal for the rotatable wheel 6. Said wheel is 55 provided with appropriate means for rotating it, indicated by the pinion 7 meshing with external teeth 8 on the wheel. These parts constitute the rotary driving mechanism with which the rectilinearly guided 60 bodies have to maintain a constant velocity ratio.

The wheel 6 has an internal flange 9 which enters the channel 4, and so retains the wheel axially in position. Said flange 65 is provided with internal teeth 10 forming between them pockets 11 for the reception of the lens casing 12. Said casings are externally cylindrical, the pockets 11 being correspondingly of approximately semi-cylindrical form. Towards their ends the cylinders are provided with flanges 13, 14 and shields 15 for the purposes mentioned below.

The closed path of the centres of the cylinders 12 comprises the portion A—B of 70 the pitch circle of the wheel 6, the transition curve B—C, the rectilinear path C—D and the transition curve D—A.

In the section A—B of their path the cylinders are carried in the pockets 11 and 75 are retained therein by the cylindrical shoulder 16 of the disc 2.

In the straight section C—D they are constrained by the plane guide surfaces of 80 the slot 5. Within this section the lenses 85 are exposed through the openings 17. In the transition curve B—C the cylinders pass out of the wheel 6 and are constrained, by the guide surfaces 18, to the straight guide 5. Similarly in the curve D—A they are 90 guided by guide surfaces 19 back into the wheel 6. So much of the guide surfaces 18 and 19 as is cut out of the disc 2 by the formation of the channel 4, is provided by 95 inserted pieces 20.

From B to A the cylinders are in contact with and push one another; their motion being derived from that tooth 10^a of the wheel 6 which is driving the cylinder leaving the pitch circle. The motion in this section is 100

preferably upwards so that the cylinders are held in contact with one another by gravity.

In the pitch circle arc A—B the cylinders are spaced apart, giving a substantial driving tooth 10 between each pocket 11 which is not possible if it is attempted to apply a driving wheel centrally to the cylinders packed in the straight path. The diameter of the pitch circle, the spacing of the cylinders therein, and the length and shape of the path section B—A are so proportioned to the diameter of the cylinders as on the one hand to fill the path section B—A sufficiently to ensure that the uppermost cylinder in it will be properly received into its pocket 11, and on the other hand to ensure that there shall be no break in the driving contact of the last tooth 10^a with the cylinder passing out of the pitch circle.

In the example shown, the path C—D is on a diameter of the pitch circle. This gives a satisfactory form to the driving tooth face 21 and has manufacturing advantages.

Whilst the transition path B—C has necessarily to be arranged to maintain uninterrupted contacts from tooth 10^a through to the last of the exposed cylinders, the transition path D—A is so arranged as to relieve the close packing of the cylinders and so avoid any danger of the cylinder train becoming jammed. It is accordingly made rather longer and of greater radius than the path B—C; this latter feature also enabling the teeth 10 to be kept sufficiently long to maintain contact with the cylinder which is being driven into section B—C.

Measurements suitable for meeting the above conditions are:

Diameter of cylindrical lens casings, 1 unit;

Number of lens casings, 14;

Number of pockets (11), 18;

Diameter of pitch circle A—B, 6.64 units; Path section C—D lies on a diameter of A—B;

Radius of arc B—C, 1 unit;

Radius of arc D—A, 1.24 units.

The driving tooth faces 21 are empirically shaped to maintain contact with the cylinder leaving the pitch circle while the wheel 6 rotates at constant speed and while the cylinders of the rectilinear section C—D move at constant speed; thus ensuring a constant velocity ratio between the wheel and the cylinders in C—D.

While the cylinders are being directly transported by the wheel 6 they are stationary within the pockets 11 and therefore not subjected to wear. When they are within the straight path they slide in the guide 5; and to give them adequate sliding contact area to resist wear, they are provided with the flanges 13, 14 the flat end faces 22 of

which make contact with the guide 5. Said end faces may be tangent to the cylinder so that they and the periphery of the cylinder contact simultaneously with the guide.

The side edges 23 of the flanges 13 may be tangent to the cylinder and at right angles to the end faces 22 to provide bearing surfaces by means of which the cylinders press upon one another when passing through the guide 5. The flanges 14 however have sloping sides 24 to permit the cylinders to be positioned angularly to one another, in the curved portions of their path.

The inner shoulders 25 of the wheel 6 and the shoulder 16 of the disc 2 engage the end faces of the flanges 13 and 14 sufficiently closely to ensure that said flanges will be properly positioned when they are presented to the guide 5. Clearances 26 are cut to clear the corners of the flanges 13 when the cylinders are passing through the transition curves B—C and D—A.

The shields 15 are provided for the purpose of blinding the triangular gaps 27 (Fig. III) left between the flanges 14 of the lenses which are being exposed. They are provided at the opposite ends of successive cylinders to allow them to overlap in the axial direction of the lenses. The end of the lens casing which does not carry a shield is cut away at 28 to give clearance to the corners of the adjacent shields as they tilt in the curves B—C and D—A.

I claim:

1. The combination of a number of similar loose bodies and means defining a closed path through which said bodies are pushed, said means including guide surfaces defining a rectilinear section of the path, and an internally toothed wheel part of the pitch circle of which defines another section of the path, the rectilinear path being on a chord of the pitch circle.

2. The combination of a number of similar loose bodies and means defining a closed path through which said bodies are pushed, said means including guide surfaces defining a rectilinear section of the path, and an internally toothed wheel part of the pitch circle of which defines another section of the path, the rectilinear path being on a diameter of the pitch circle.

3. The combination of a number of similar loose bodies and means defining a closed path through which said bodies are pushed, said means including guide surfaces defining a rectilinear section of the path, an internally toothed wheel part of the pitch circle of which defines another section of the path, and guides defining transition curves between the pitch circle and the rectilinear section, the transition curve at one end of the rectilinear section being of greater radius than that at the opposite end of said section thereby to maintain constant con-

tact through a series of the bodies beginning with the one about to leave the wheel and including those in the rectilinear section.

4. The combination of a number of similar loose bodies and means defining a closed path through which said bodies are pushed, said means including guide surfaces defining a rectilinear section of the path, an internally toothed wheel part of the pitch circle of which defines another section of the path, and guides defining transition curves between the pitch circle and the rectilinear section, and a number of similar loose bodies, a group of which 10 completely fills that portion of the path which consists of the rectilinear section and the transition curve giving exit from the rectilinear section being longer than the 15 other transition curve to avoid close packing of the bodies between the rectilinear section and the wheel.

5. The combination of a number of loose cylindrical bodies, an internally toothed 20 driving wheel adapted to receive such bodies between its teeth, a rectilinear guide for the bodies, curved guides guiding the bodies from the wheel into one end of the rectilinear guide and from the other end of the 25 rectilinear guide back into the wheel, and flanges on the bodies having flat end faces which contact with the rectilinear guide.

6. The combination of a number of loose cylindrical bodies, an internally toothed 30 driving wheel adapted to receive such bodies between its teeth, a rectilinear guide for the bodies, curved guides guiding the bodies from the wheel into one end of the rectilinear guide and from the other end of the 35 rectilinear guide back into the wheel and flanges on the bodies having flat edges which contact with one another when the bodies are in the rectilinear guide.

7. The combination of a number of loose 40 cylindrical bodies, an internally toothed driving wheel adapted to receive such bodies between its teeth, a rectilinear guide for the bodies, curved guides guiding the bodies from the wheel into one end of the rectilinear guide and from the other end of the 45 rectilinear guide back into the wheel, contact-making flanges on the bodies sloped to permit the bodies to pass around curves, and shields to blind the gaps left between the 50 sloped flanges.

8. The combination of a number of similar loose bodies and means defining a closed path through which said bodies are pushed, said means including guide surfaces defining a rectilinear section of the path, and an internally toothed wheel part of the pitch circle of which defines another section of the path, the rectilinear path being on a chord of the pitch circle and the teeth of the wheel 55 having driving faces adapted to maintain contact with said bodies during their passage to the rectilinear section thereby to impart to the bodies in said section a constant velocity relatively to the velocity of the 60 toothed wheel.

9. The combination of means defining a closed path through which a number of loose bodies are pushed, said means including guide surfaces defining a rectilinear section of the path, an internally toothed wheel 70 part of the pitch circle of which defines another section of the path, and guides defining transition curves between the pitch circle and the rectilinear section, and a number of similar loose bodies, a group of which 75 completely fills that portion of the path which consists of the rectilinear section and the transition curve giving entry to the rectilinear section, said group including the body about to leave the wheel and each body 80 in said group being in physical contact with the next, the remainder of the bodies occupying the remainder of the path but incompletely filling the same.

Signed at Johannesburg, Transvaal Province, Union of South Africa, this 4th day of October, 1927.
